W. C. HART.
PRINTING PRESS INK FOUNTAIN,
APPLICATION FILED NOV. 23, 1916.

Patented Oct. 30, 1917.

2 SHEETS—SHEET 2.

UNITED STATES PATENT OFFICE.

WILLIAM C. HART, OF ST. LOUIS, MISSOURI.

PRINTING-PRESS INK-FOUNTAIN.

1,244,979.

Specification of Letters Patent. Patented Oct. 30, 1917.

Application filed November 23, 1916. Serial No. 133,037.

To all whom it may concern:

Be it known that I, WILLIAM C. HART, a citizen of the United States, residing at the city of St. Louis, State of Missouri, 5 have invented certain new and useful Improvements in Printing-Press Ink-Fountains, of which the following is a specification, reference being had to the accompanying drawings, forming a part thereof.

10 This invention relates generally to disk-platen job printing-presses and, more particularly, to certain new and useful improvements in ink-fountains especially adapted for use in connection with presses of the kind 15 stated.

One of the objects of my present invention is to provide a disk-platen printing-press with an ink-fountain with which the type-inking or feeding rolls, of which there are 20 usually a plurality, in their upward travel toward the main inking-disk are each adapted to engage or contact with the fountain-roll in advance of reaching the inking-disk, whereby ink from the fountain is evenly and 25 smoothly distributed by the inking-rolls upon and over the inking-disk, the several inking rolls in their upward travel each carrying a daub of ink from the fountain and, to a certain extent, spreading the same upon 30 the disk and in their downward travel toward the type further spreading or distributing over the disk the ink carried thereupon by the rolls in their upward travel.

Another object of my present invention is 35 to provide a printing-press of the kind mentioned with an ink-fountain which is adapted to be alternately, in and during the operation of the press, thrown or rocked into and out of operative ink-supplying position 40 relatively to the type-inking or feeding rolls, so that the inking-rolls will engage with the fountain roll only when and as the inking-rolls travel upwardly toward the inking-disk of the press, the inking-rolls traveling in 45 front of the fountain-roll, but without engaging or contacting therewith, when traveling downwardly to ink the type, whereby the type is uniformly inked throughout and daubs of ink upon the type avoided and 50 neater and cleaner printing-jobs obtained.

A further object of my present invention is to provide a printing-press of the kind 55 stated with an ink-fountain which is adapted to be thrown or rocked into and out of operative ink-supplying position relatively to the type-inking or feeding rolls simul-

taneously with and as the throw-off lever of the press is actuated to throw the type-bed and platen of the press into and out of operative printing position. 60

A still further object of my present invention is to provide an ink-fountain for presses of the kind referred to which is comparatively simple and inexpensive in form and construction, and which is adapted to 65 be conveniently attached operatively upon the press.

With the above and other objects in view, my present invention resides in certain novel features of form, construction, arrangement, 70 and combination of parts, all as will hereinafter be described and afterward pointed out in the claims.

In the accompanying drawings,—

Figure 1 is a fragmentary side elevational 75 view of a disk-platen job-printing-press equipped with an ink-fountain embodying my invention;

Fig. 2 is a fragmentary rear elevational view of the same; 80

Fig. 3 is a side elevational view of the fountain in non-ink-supplying position relatively to the type-inking or feeding rolls;

Fig. 4 is a slightly enlarged side elevational view of the fountain in ink-supplying 85 position relatively to the type-inking rolls;

Figs. 5 and 6 are, respectively, plan and front elevational views of the same;

Fig. 7 is also a side elevational view of the fountain and its associate parts, the fountain being again shown in non-ink-supplying position relatively to the type-inking rolls;

Fig. 8 is a similar view with the fountain in ink-supplying position relatively to the 95 type-inking rolls;

Fig. 9 is a perspective view of an adjustable cover-plate which I prefer to employ with my new fountain to reduce the ink-delivering surface of the fountain roll; 100

Fig. 10 is a plan view of the fountain equipped with the adjustable cover shown in Fig. 9;

Fig. 11 is a longitudinal sectional view through the fountain on approximately the 105 line 11—11, Fig. 10; and

Fig. 12 is a front elevational view of the fountain shown in Fig. 10.

Referring to the said drawings, in which like reference characters refer to like parts 110 throughout the several views, my ink-fountain is especially adapted for use with disk-

platen job printing-presses of present standard construction; and I have here shown only such parts of a press of the kind mentioned necessary for the purpose of illustrating the operative connection therewith of an ink-fountain embodying my invention. Of the press shown, 1 indicates a portion of the frame. Pivoted upon the frame 1 is the type-bed portion 2 of the press. Jounaled upon the press-portion 2, is the usual back cross-shaft 3, mounted upon each end of which is a roller-frame 4, the roller-frames 4, which are connected by a rear cross-piece 5, supporting and carrying the type-inking or feeding rolls 6, three in number in the present machine. Suitably journaled upon the press is a disk or gear 7, pivotally attached eccentrically at one end to which is a rod 8 also pivotally attached at its other end to an offset 9 on shaft 3. Pivotally fastened at one end to a fixed part of the press is an arm 10 having its other end pivotally attached to an upwardly projecting portion 11 of the roller frame 4. Suitably mounted for rotation upon the press portion 2 is the usual main inking disk 12.

In the operation of the press, as will be understood, on the rotation of gear or disk 7, the roller frames 4 will be rocked to carry the inking rolls 6 upwardly upon disk 12, then downwardly upon disk 12 and across the type-bed 13 of the press, and then upwardly again, etc. Of the press, 14 indicates the throw-off lever, which is suitably pivoted upon the frame 1. Pivotally fastened at one end to the lower end of lever 14 and at its other end to an arm 15 pivotally mounted upon the frame 1 is a link 16. 17 indicates a bell-crank lever also pivoted upon the frame 1, one arm 18 of lever 17 being longitudinally provided with a slot 18', working in which slot 18' is a roller 19 mounted on the arm 15. Pivotally attached at its lower end to the other arm 20 of lever 17, and at its other end to offset 9 of shaft 3, is a rod 21.

Normally, as when lever 14 is in the position thereof shown in Fig. 1, the platen (not shown) of the press and the type-bed will, in the operation of the press, be alternately brought into and out of printing position relatively to each other; on throw-off lever 14, however, being actuated to the left or in the direction of the arrow shown in Fig. 1, the back shaft 3 will, through the parts described, be rotarily moved to a certain extent sufficiently to throw the type-bed portion 2 of the press out of printing position relatively to the platen, should the press be continued in operation, all as will be fully understood.

The ink fountain includes a box-like receptacle open at its top and front side and comprising a bottom wall 22, a rear wall 23, and side walls 24-24. Disposed obliquely within the box and fastened at its rear end to an

enlargement 25 of rear wall 23, is a more or less spring-plate 26 yieldingly bearing at its forward end upon the upper face of bottom wall 22.

Jounaled in the side walls of the box 70 and extending across the box at its forward end is a shaft 27, fixed upon which, to rotate within the box, is a roller 28. Disposed longitudinally of the box and threaded through its rear wall 23, is one or more adjusting screws 29 adapted to engage at their forward ends with plate 26 to adjust the position of the forward end of plate 26 relatively to roller 28 to regulate the flow of ink from the fountain. Bottom wall 22 is 80 provided with a depending lug 30 which is adapted to adjustably seat in a longitudinal recess or slot 31' provided in an elongated strip or plate 31, the box being adjustably secured to plate 31 as by means of a bolt 85 32. The strip or plate 31 is provided with a depending eye 33 adapted to be pivotally fastened to suitable perforated ears 34 on a second plate or strip 35. This plate 35 is provided longitudinally at its rear end 90 with a slot, as at 36, to adjustably receive a fastening bolt 37 for securing the fountain upon the press. Interposed between the plates 31 and 35 at their forward end, and suitably held in position, as by means of a 95 stud 33', is a coiled spring 36' adapted to yieldingly maintain plate 31 and the fountain box mounted thereupon in properly spaced relation from lower plate 35. The plate 35 and the parts just described are 100 adjustably fastened upon the type-bed portion 2 of the press at a suitable point below disk 12, and in operative position relatively to inking rolls 6, so that the inking rollers 6, in their upward travel toward disk 12, will 105 engage with fountain roll 28 in advance of reaching inking disk 12. Further, each roller 6, in its upward travel, will in turn engage with fountain roll 28 and carry a daub of ink therefrom to and upon the disk 110 12, the rollers 6, in their continued upward travel spreading upon the disk 12 the ink so carried thereupon, and afterward, in their downward travel, further spreading upon the disk the ink so carried thereupon by the 115 rolls 6 in their upward travel, whereby the ink upon the disk 12 is evenly and smoothly distributed thereupon and daubs of ink avoided upon the rollers 6 and consequently also upon the type. 120

Fastened at one end, as by a clamp 38 to roller frame 4, is a link 39, pivotally connected at its other end to one end of a second link 40, link 40 having its other end loosely fastened to an extension 41 of shaft 27. 125

Fixed upon extension 41 of shaft 27 is a ratchet wheel 42, engaging with which is a pawl 43 pivoted upon the link 40. As roller frame 4 is rocked or reciprocated in the operation of the press, fountain roll 28 will, 130

through ratchet wheel 42 and its coöperating pawl 43, be step by step rotated to present a fresh ink supplying surface to the type inking or feeding rolls 6 as the same are moved upwardly to carry ink from the fountain to the disk 12.

Loosely sleeved on shaft 3 is a collar or the like 44, provided with a cam-portion 45. The collar 44 is provided with a pair of laterally projecting spaced pins 46, with which is adapted to engage a notched spring 47 fastened to and upon the press; as seen particularly in Figs. 3, 4, 7, and 8, to prevent lateral movement of the collar 44 upon the shaft 3.

Threaded into collar 44 at approximately right angles to each other is a pair of rocker-arms 48 and 49, the arm 48 being provided with a lateral extension 50.

20 Fountain plate 31 is provided at its rear end with a bored portion 51, adjustably fastened in which, as by set-screw 52, is a short staff or rod 53 carrying a roller 54 at its lower end, the roller 54 being adapted to roll upon and engage with the collar 44 and its cam-portion 45. Reference being now had particularly to Figs. 7 and 8, it will be seen that when the roller 54 is out of engagement with cam-portion 45 of collar 44, 25 the fountain box and its roller 28 will be in ink supplying position relatively to inking rolls 6, so that said rolls 6, when moving upwardly, engage with the fountain roll 28 to take ink therefrom to disk 12.

30 The inking rolls 6 having reached their uppermost position upon the disk 12 and roller frames 4 being now, in the operation of the press, actuated to carry the rollers 6 down from disk 12 and across the type-bed, the roller frames will, at their cross-piece 5, engage with the rocker arm 49 and throw the same into the position thereof illustrated in Fig. 7. In such movement of rocker arm 49, collar 44 will be rotarily moved on shaft 3 to bring its cam-portion 45 beneath roller 54, whereupon the fountain will be thrown, against the resiliency or tension of spring 36', into the position thereof illustrated in Fig. 7 out of the path 35 of rollers 6, so that said rollers 6 in traveling toward the type 2 will escape any contact or engagement with the fountain roller 28. Thus I avoid daubs of ink being carried upon the type from the fountain and obtain cleaner and neater printing jobs.

On the roller frames being again actuated to carry rollers 6 upwardly, the roller frame 4 shown will engage with extension 50 of arm 48, throwing the same from the position thereof shown in Fig. 7 to the position thereof shown in Fig. 8. In such movement of arm 48, collar 44 will be reversely moved on shaft 3 to carry its cam-portion 45 from beneath roller 54, whereupon the fountain, under the influence of spring 36',

will return to ink supplying position relatively to the inking rolls 6, the fountain roll 28 being then in the path of rolls 6 as the latter are caused to move upwardly.

Fixed upon the shaft 3 is a second collar 70 or ring 55 having a cam-portion 56. Rotarily bearing upon this collar 55 is a second roller 57, also carried by the rod 53, as more particularly shown in Fig. 6. Normally, as when throw-off lever 14 is in the 75 position thereof illustrated in Fig. 1 and the platen and type-bed are in operative printing relation, roller 57 is out of engagement with the cam-portion 56 of second collar or ring 55, and the fountain and its 80 roll 28 are free to be rocked relatively to the inking rolls 6 as heretofore described. When, however, throw-off lever 14 is actuated to throw the platen and type-bed out of printing relation, collar 55, with its 85 supporting shaft 3, will be rotarily moved to bring cam-portion 56 thereof beneath roller 57, whereupon the fountain box and its roll 28 will be depressed, against the tension of spring 36', into non-ink supplying position 90 relatively to the inking rollers 6, and held in such position as long as lever 14 is in throw-off position, so that, should the press be continued in operation, rollers 6 in their travel will escape any contact with the fountain roll 28.

It may be desirable, as when printing small jobs, to reduce the ink-supplying surface of fountain-roll 28. For this purpose, I provide the cover-plate 58 shown particularly in Fig. 9. This plate 58, which is adapted to fit over and upon the fountain-box and its roll 28 as illustrated in Figs. 10, 11, and 12, is provided with bent end-portions 59 and 60 slotted transversely, as at 61 105 and 62, respectively, to accommodate fastening-screws 63—63. Thus the plate 58 may be adjustably fastened laterally upon the box and more or less of the ink-supplying periphery of fountain-roll 28, as may be desired, presented for engagement with the inking-rolls 6 as the latter are oscillated or rocked upwardly toward the inking-disk 12.

I am aware that changes in the form, construction, arrangement, and combination of 115 the several parts of my new ink-fountain may be made and substituted for those herein shown and described without departing from the nature and principle of my invention.

Having thus described my invention, what I claim and desire to secure by Letters Patent is:

1. The combination with a printing-press of the kind described, the same including a 125 back-shaft and an oscillatory roller-frame and inking-roll, of an ink-fountain pivotally mounted upon the press, the fountain including an ink-supplying roll, means for yieldingly maintaining the fountain and its 130

roll in ink-supplying position relatively to the inking-roll on the oscillation of the inking-roll from the type-bed of the press, and means actuated by the roller-frame for pivotally rocking the fountain and its roll out of ink-supplying position relatively to the inking-roll on the oscillation of the inking-roll toward said type-bed, said last-named means including a cam-member on the back-shaft and a member on the fountain adapted to coöperate with said cam-member.

2. The combination with a printing-press of the kind described, the same including a back-shaft and an oscillatory roller-frame and inking-roll, of an ink-fountain pivotally mounted on the press, the fountain including an ink-supplying-roll, a collar rotatably movable on said shaft, said collar having a cam-portion, a roller on the fountain adapted for engagement with the cam-portion of the collar, rocker-arms on said collar, said arms being actuated by the roller frame in its oscillations to move the cam-portion of the collar into and out of engagement with said roller to rock the fountain and its roll out of ink-supplying position relatively to said inking-roll on the oscillation of the inking-roll toward the type-bed of the press, and a spring for yieldingly returning the fountain and its roll into ink-supplying position relatively to the inking-roll on the oscillation of said inking-roll from said type-bed.

3. The combination with a printing-press of the kind described, including its inking-roll and throw-off mechanism, of an ink-fountain movably mounted on the press intermediate the type-bed and inking-disk thereof, the fountain including an ink-supplying roll, a spring interposed between the press and the fountain for yieldingly maintaining the fountain and its roll in ink-supplying position relatively to the inking-roll when the throw-off mechanism is in on position, and means for actuating the fountain and its roll out of ink-supplying position relatively to said inking-roll simultaneously with the actuation of the throw-off mechanism to off position.

50 4. The combination with a printing-press of the kind described, including its inking-roll and throw-off mechanism, of an ink-fountain pivotally mounted on the press, the fountain including an ink-supplying

roll, means for yieldingly maintaining the fountain and its roll in pivotally elevated ink-supplying position relatively to the inking-roll when the throw-off mechanism is in on position, and means for pivotally lowering the fountain and its roll out of ink-supplying position relatively to the ink-roll when the throw-off mechanism is actuated to off position, said means including a cam-member fixed upon, and movable with, the back-shaft of the press, and a member on the fountain coöperatively engaging with said cam-member.

5. The combination with a printing-press of the kind described, including its inking-roll, back-shaft, and throw-off mechanism, of an ink-fountain pivotally mounted on the press, said fountain including an ink-supplying roll, a spring for yieldingly maintaining the fountain and its roll in ink-supplying position relatively to the inking-roll when the throw-off mechanism is in on position, a collar fixed on said shaft, said collar having a cam-portion, and a roller on the fountain normally engaging with said collar, the cam-portion of said collar being thrown into engagement with said roller to rock the fountain and its roll out of its said ink-supplying position when the throw-off mechanism is actuated to off position.

6. The combination with a printing-press, of a plate mounted to rock upon the press, an ink-fountain on the forward end of said plate, a spring interposed between the press and the forward end of the plate for yieldingly maintaining the plate and fountain in normal ink-supplying position, and means at the rear end of the plate engageable with the press for rocking the plate and fountain against the tension of said spring.

7. The combination with a printing-press, of a box-like receptacle for containing ink mounted on the press, an ink-roller journaled on said receptacle, a plate 58 adapted to extend over, and provide a cover for, both said receptacle and roller, said plate being slotted, and attaching-members extending through the slots of the plate and into the receptacle for fastening the plate in adjusted positions upon the receptacle.

In testimony whereof, I have signed my name to this specification.

WILLIAM C. HART.
